UNITED STATES PATENT OFFICE.

NICK SCOURTES AND PAUL KAROUZOS, OF DETROIT, MICHIGAN.

TOY AEROPLANE VEHICLE.

Application filed January 19, 1927. Serial No. 161,991.

Our invention relates to a new and useful improvement in a toy aeroplane vehicle, and has for its object the provision of a vehicle simulating in appearance, and somewhat in 5 operation, an aeroplane, and adapted for being propelled over the ground by a child.

Another object of the present invention is the provision of a vehicle of this class which may be easily and quickly assembled to accommodate either one or two persons.

Another object of the invention is the provision of a mechanism whereby the vehicle may be propelled by the rudder when used for one person, or when used for carrying two 15 persons.

Another object of the invention is the provision of a rudder which may be moved at the time the vehicle is steered so as to simulate steering by the rudder itself.

Another object of the invention is the provision of a movable tail member on a toy of this kind which may be operated at will.

Another object of the invention is the provision of wings on the device which may be so adjusted as to utilize for propelling purposes such wind as may be encountered when the vehicle is being used.

Other objects will appear hereinafter.

The invention consists in the combination 30 and arrangement of parts hereinafter described and claimed.

The invention will be best understood by a reference to the accompanying drawings which form a part of this specification and 35 in which,

Fig. 1 is a top plan view of the invention.

Fig. 2 is a side elevational view of the invention.

Fig. 3 is a front elevational view of the invention.

Fig. 4 is a sectional view taken on line 4—4 of Fig. 2.

Fig. 5 is a sectional view taken on line 5—5 of Fig. 1.

Fig. 6 is a sectional view taken on line 6—6 of Fig. 1.

Fig. 7 is a sectional view taken on line 7—7 of Fig. 2.

Fig. 8 is a sectional view taken on line 8—8 of Fig. 7.

As shown in the drawings, the invention comprises a body which is made of a rear section 7, a central removable section 8 and a forward section 9. The rear section 7 is

adapted to overlap with the flange 10 the rear end of the removable section 8, the section 8 having hooks 11 which serve to secure the rear end of the section 8 to the forward end of the section 7. Similar hooks 12 are carried by the forward section for engaging the front end of the removable section 8. A suitable seat 13 is mounted in the section 8 and extending transversely of the section. A crank 14 having pedals 15 mounted thereon so that by rotating the crank through the operation of the pedals, a reciprocation of the connecting rods may be effected, these connecting rods attaching to the crank shaft 17 upon which the wheels are fixedly mounted, these wheels being journalled in suitable bolsters 19, depending from the bottom of the section 9. A seat 20 is mounted in the section 9 so that the user, by operating the pedals 21, may effect a rotation of the crank shaft 17, to propel the vehicle. Projecting vertically at the forward end of the section 9 is a rod 22 having the angularly turned portion 23, this rod being adapted to effect a rocking of the transversely extending rod 24 which is connected at its opposite ends by the rods 25 and 26 to a cross member 28 which is fixedly attached to the cross head 28 of the bolster to which is pivotally attached the bracket 29 carrying the wheel 30, so that a swinging of the member 23 in either direction will effect a steering of the vehicle. The rod 25 is extended beyond the cross head 28 with the portion 31 and attached to an outwardly extending arm 32 which is connected to the rudder 33, this rudder being pivotally mounted on the bolt 34 so that as 90 the vehicle is steered, the rudder 33 will also be moved angularly to simulate a steering by means of the rudder.

As shown in Fig. 2, the rods 25 are each provided with a section 35 which may be 95 removed when the middle section 8 is dispensed with.

A tail piece 36 is pivotally mounted on the bolt 37 and provided with the upwardly extending arm 39 which is connected to the rod 40 in which is positioned a removable link 41, this rod 40 connecting to the upwardly extending lever 42, so that the operator may at will rock the tail downwardly or upwardly, as shown in Fig. 2.

When the middle section 8 is removed, the connection of the rod 16 with the crank shaft 17 will also be removed, thus connecting the

section 7 directly with the section 9 and making a shorter vehicle, and one which operates in the manner described.

Projecting outwardly from the section 9 at opposite sides, are wings 43 and 44, each of these wings being pivotally mounted, as shown in Fig. 2, and adapted for being swung downwardly by the arms 45 and 46 into a position extending the wings inclined to the horizontal or vertically thereto, so as to present a body for catching the wind and assisting in propelling the vehicle.

Mounted on the forward end of the section 9 is a rotatable rudder 47 which, when the vehicle is propelled at a fairly high rate of speed, will be caused to rotate.

In this manner we have provided a vehicle which is quite simple in its structure, easily and quickly assembled for accommodating one or two persons, and which is possessed of novel features of construction, permitting the adjustment of the device to various forms and affording considerable means of amusement to the occupant while riding in the vehicle.

While we have illustrated and described the preferred form of our invention, we do not wish to limit ourselves to the precise form of structure shown, but desire to avail ourselves of such variations and modifications as may come within the scope of the appended claims.

Having thus described our invention what we claim as new and desire to secure by Letters Patent is:

1. A vehicle of the class described comprising: a body portion formed from a plurality of sections; means for attaching said sections together; a steering traction wheel carried by said vehicle; sectional means extending from the forward part of said vehicle to said steering traction wheel for operating the same, one of the sections of said body and one of the sections of said means being removable at will, said attaching means being operative for attaching adjacent ends of remaining sections together after the removal of said one section.

2. A vehicle of the class described having a body portion comprising: a front, center and rear section; means for attaching said center section to the forward end of said rear section, and the rearward end of said forward section, said center section being removable at will, said attaching means, upon the removal of said center section serving to attach the rearward end of said forward section to the forward end of said rearward section; a steering traction wheel carried by said rearward section; means extending to the forward section for operating said steering traction wheel, said means being sectional and provided with a central section remov-

able at will, said central section being dispensed with upon elimination of said central body section.

3. A vehicle of the class described having a body comprising: a forward section, a central section and a rearward section; means for attaching said central section to the forward end of said rearward section and the rearward end of said forward section; traction wheels mounted on said forward section; means accessible to an occupant of said forward section for rotating said traction wheels; operating pedals in said central section accessible to an occupant thereof; and means for connecting said operating pedals operatively to said traction wheels for effecting the rotation of said traction wheels upon the operation of said operating pedals, said traction wheels being rotatable by an occupant in the forward section and in the rearward section simultaneously, said central section being removable at will, and said attaching means serving to connect the rearward end of said forward section with the forward end of said rearward section, said connecting means being eliminated upon the removal of said central section.

4. A vehicle wheel of the class described having a body comprising: a forward section, a central section and a rearward section; means for attaching said central section to the forward end of said rearward section and the rearward end of said forward section; traction wheels mounted on said forward section; means accessible to an occupant of said forward section for rotating said traction wheels; operating pedals in said central section accessible to an occupant thereof; means for connecting said operating pedals operatively to said traction wheels for effecting the rotation of said traction wheels upon the operation of said operating pedals, said traction wheels being rotatable by an occupant in the forward section and in the rearward section simultaneously, said central section being removable at will, and said attaching means serving to connect the rearward end of said forward section with the forward end of said rearward section, said connecting means being eliminated upon the removal of said central section; a steering traction wheel carried by said rearward section; sectional means connected to said steering traction wheel for operating the same and extending to the forward part of said forward section, the central section of said operating means being removable upon the removal of said central body section.

In testimony whereof we have signed the foregoing specification.

NICK SCOURTES.
PAUL KAROUZOS.
